(57) **CLAIM**

The ornamental design for a LED advertisement screen as shown and described.

DESCRIPTION

1. LED advertisement screen

1.1 is a front, left and bottom perspective view of the first embodiment of a LED advertisement screen, showing my design.

1.2 is a rear, right and top perspective view thereof.

1.3 is a front elevation view thereof.

1.4 is a rear elevation view thereof.

1.5 is a left side elevation view thereof.

1.6 is a right side elevation view thereof.

1.7 is a top plan view thereof.

1.8 is a bottom plan view thereof.

1.9 is an enlarged view of portion 1.9 in 1.1.

1.10 is an enlarged view of portion 1.10 in 1.1.

1.11 is an enlarged view of portion 1.11 in 1.1.

The dashed broken lines depict portions of the LED advertisement screen that form no part of the claimed design.

The dot-dash broken lines surrounding details shown in 1.1 and 1.9-1.11 are for the purposes of annotating the enlarged view only and form no part of the claimed design.
